UNITED STATES PATENT OFFICE.

FRANK JOSEPH FEELY, OF BURWYN, ILLINOIS, ASSIGNOR TO WESTERN ELECTRIC COMPANY, INCORPORATED, OF NEW YORK, N. Y., A CORPORATION OF NEW YORK.

REEL.

Application filed August 27, 1923. Serial No. 659,511.

This invention relates to reels, and more particularly to a reel adapted to support cable during the shipment thereof.

A reel which may be satisfactorily used for storing cable during the shipment thereof should be economical of construction, but it must be strong enough to carry a long section of cable, which is usually of great weight, safely to its destination.

An object of the present invention is to simplify and cheapen the construction of a reel without deleteriously affecting its strength.

A reel made in accordance with this invention may comprise an axial tube with a flanged metal hub at either end, a wooden head being secured between each hub flange and an internal metal ring, while wooden lags supported by the heads, and wooden discs intermediate the heads, are held in place by encircling metal bands, tie bolts parallel to the lags being employed to connect the heads.

These and other features of the invention not specifically mentioned will appear from the following description and the accompanying drawings, in which

Fig. 1 is a view in side elevation, partly in section, and

Fig. 2 is a view in end elevation of a reel made in accordance with this invention.

Referring to the drawings in detail, in which similar reference characters denote similar parts throughout the various figures, an axial tube 10 of metal has inserted in either end thereof annular flanged members 12 to serve as hubs, while upon the tube at either end, and bolted between the flange of the hub and an internal annular metal member 14, are bolted circular wooden heads 16. These heads may be built up by nailing, or otherwise securing together, several courses or layers of wooden boards, the grain of each succeeding course of which is laid at an angle to that of the previous one, the interior course or courses 18 being cut to have a diameter equal to that of the interior of a drum composed of wooden lags or strips 22 supported by the interior course or courses.

Intermediate the heads, and having a ring fit upon the axial tube, are wooden discs 20 for assisting in the support of the lags 22. These discs also have a diameter equal to that of the interior of the drum

and although in the illustration three are shown, it is evident that the number of discs employed may vary according to the size of the reel and the nature of the cable to be shipped.

The lags 22 which may either be in engagement with each other or held at any desired distance apart by spacers 24, may be of wood, while parallel to the lags, and extending the entire length of the reel, are tie bolts 26 which tend to draw the heads together and bind the reel into a unit, metal washers 28 being used to afford a bearing for the nuts of the bolts 26 and to protect the wooden reel heads. Bolts 30, also provided with washers, are employed to bind together the layers of which the heads are constructed and thereby strengthen the reel. Intermediate the wooden discs 20, and parallel to the lags, are spacers 21 for positioning the discs, and which may consist of wooden cleats nailed to the interior of the lags. Encircling the lags radially opposite each supporting disc, are bands of metal 32 which are here shown as double straps of band iron, and are for the purpose of securing the lags firmly in position.

An opening 34 may be provided in one head just beyond the drum to provide means for securing an end of the cable 35 therein when starting to wind it on the reel and this opening is of a shape well known in the art of reel construction. A depression 35 may also be provided in one head to permit the insertion of a pin for rotating the reel while winding the cable thereon.

What is claimed is:

1. In a reel, a tubular central member, flanged annular hubs associated with the ends thereof, annular members associated with the hub flanges, heads secured between each hub flange and associated annular member, a drum intermediate the heads, and means for securing the heads to the drum.

2. In a reel, a tubular central member, flanged annular hubs associated therewith, heads associated with the hubs and having reduced portions, discoid members closely surrounding the tubular central member intermediate the heads, and a drum encircling and supported by the discoid members and the reduced portions of the heads.

3. In a reel, a tubular central member, hubs associated with the central member, an annular member associated with each hub,

heads connected to the hubs and the annular members, a discoid member associated with the central member, and means surrounding the discoid member and supported by the heads to form a drum.

4. In a reel, a tubular central member, flanged annular hubs inserted in the ends thereof, an annular clamping member associated with each hub, heads secured between 10 the hub flanges and the annular clamping members, discs closely surrounding the tubular central member intermediate the heads, and a plurality of lags supported by said discs to form a drum.

5. In a reel, a tubular central member, flanged annular hubs associated therewith, heads associated with the hub flanges, a disc intermediate the heads for supporting a drum, spacing members intermediate the 20 heads and the disc, and lags intermediate the heads and supported by the discs to form a drum.

6. In a reel, a tubular central member, flanged annular hubs inserted in the ends 25 thereof, an annular clamping member associated with each hub, built up wooden heads clamped between the hub flanges and

the annular clamping members, wooden discs intermediate the heads, spacing members intermediate the support discs for securing them in place, and a plurality of wooden lags intermediate the heads and supported by the heads and the support discs to form a drum.

7. In a reel, a tubular central member, flanged annular hubs inserted in the ends thereof, an annular clamping member associated with each hub, heads comprising a plurality of laminations of wood, the grain of each succeeding lamination being at an angle to that of the preceding one, said heads being secured between the hub flanges and the annular clamping rings, wooden discs intermediate the heads and having a ring fit on the tubular central member, 45 spacers intermediate the discs to secure them in place, a plurality of lags supported by the heads and the wooden discs intermediate the heads, and a metal band closely encircling the lags.

In witness whereof, I hereunto subscribe my name this 15th day of August A. D., 1923.

FRANK JOSEPH FEELY.
